(57) **CLAIM**

The ornamental design for an archery bow cam, as shown and described.

DESCRIPTION

FIG. 1 is an angled isometric view of the archery bow cam.

FIG. 2 is a right side view of the archery bow cam.

FIG. 3 is a left side view of the archery bow cam.

FIG. 4 is a bottom view of the archery bow cam.

FIG. 5 is a top view of the archery bow cam.

FIG. 6 is a front view of the archery bow cam; and,

FIG. 7 is a back view of archery bow cam.

Broken lines in the drawings are for illustrative purposes only and form no part of the claimed design.
